MOP WRINGING DEVICE

Filed May 24, 1930

UNITED STATES PATENT OFFICE

MILTON BOWEN MCCOY, OF PUEBLO, COLORADO

MOP WRINGING DEVICE

Application filed May 24, 1930. Serial No. 455,839.

This invention relates to a mop wringing device.

An object of my invention is the production of a simple and efficient device which will allow the mop cloth to be easily and securely attached, and which will efficiently wring said cloth at the will of the operator.

Another object of my invention is the provision of efficient clamping means in a mop wringing device, preferably carried upon the outer end of the handle.

A still further object of my invention is the provision of certain improvements upon the construction of a mop wringing device as disclosed in my prior United States Patents, Number 1,062,984, May 27, 1913 and Number 1,046,829, Dec. 10, 1912.

With the foregoing and other objects in view, my invention comprises certain novel constructions, combinations and arrangements of parts as will be hereinafter fully described, illustrated in the accompanying drawings, and more particularly pointed out in the appended claims.

25 In the drawings:

Figure 1 is a perspective view of a device constructed in accordance with the present invention.

Figure 2 is a perspective view of a device 30 constructed in accordance with the present invention, partly shown in section, and also showing the movable clamping jaw in a closed or locking position.

Figure 3 is a sectional view taken on line 35 3—3, Figure 1, and looking in the direction of the arrows.

Figure 4 is a sectional view taken on line 4—4, Figure 2, and looking in the direction of the arrows.

40 Figure 5 is a perspective view of the primary section of the movable clamping jaw while

Figure 6 is a perspective view of the auxiliary section of said jaw.

45 Referring to the drawings by numerals, 1 designates the handle, which is preferably round two-fifths of its length and square in cross section three-fifths of its length.

50 A large split sleeve 2 is slidably mounted on the handle. A bracket band 3 is passed

around sleeve 2 and is riveted at 4 thereto, Fig. 1. This band is formed into an eye 5 with one end 6 folded back between part of the band 3 and the end 7, with rivet 8 fastening the parts together, Fig. 3. The eye 5 constitutes a journal, in which the crank shaft 9 is mounted. This crank shaft has an inner sleeve 10 and an outer sleeve 11 thereon for bracing the shaft; these sleeves 10 and 11 have no longitudinal play on the shaft; at their inner ends they bear against washers 12. The outer end of the crank shaft is provided with a revolvable grip 13, and its inner end is provided with an integral elongated eye 14.

The jaw carrying frame 15 has its ends 16 and 17 bent at right angles and extending into the handle 1, as shown by dotted lines 18. A collar 19 is placed over these ends 16 and 17, with the bolt 20 fastening the collar securely to the outer end of the handle 1. The fixed jaw 21 is formed by folding a blank over the outer part of the elongated frame 15, passing rivets 22 through the overlapping parts (Fig. 4) fastening the fixed jaw on the frame. This jaw has teeth 23 on its inner edge for better gripping the cloth 24.

A movable clamping jaw is mounted upon frame 15 and this jaw comprises primary section 25 and the auxiliary section 26. The primary section 25 comprises a straight body 27 having an outwardly projecting gripping flange 28. This body 27 is looped at 29 around the outer end of frame 15, upon which end said primary section pivots. The outer end of body 27 is provided with a laterally extending apertured lug 30. The auxiliary section 26 comprises body 31 with a slot 32 in its outer end into which lug 30 extends when the two sections are closed together. A latch 33 is pivoted at 34 on body 31, and this latch is provided with a tongue 35 that extends into the aperture of lug 30 for holding sections 25 and 26 closed together. Body 31 is provided with an outwardly extending gripping flange 28a.

Latch 33 is provided with a grip 33a which enables the operator to easily manipulate the latch. The body 31 is folded at 36 around an end of frame 15 similar to the end 29 of body 27.

The cloth 24 is threaded through frames 14 and 15 with the loose ends placed against teeth 23 of fixed jaw 21 and then the movable sections of the movable clamping jaw are closed down upon the cloth, with the gripping flanges 28 and 28a tightly engaging the cloth, thereby holding the cloth securely in position on the device.

When the mop cloth 24 has been positioned upon the device, and the mopping is to be done, then the crank shaft and its parts are slid downward upon the handle to the position shown in Fig. 2. When the mop is to be wrung, the sleeve 2 and crank shaft 9 are slid upwardly on the handle to the position shown in Figure 1, whereby the operator can easily wring the cloth 24 by rotating said shaft.

The fastening of the jaw carrying frame 15, in the manner specified, makes a strong and durable device. The preferred form of the sleeve 2 and bracket band 3 is shown and described, but it may be constructed of one piece of molded iron or sheet metal.

While I have described the preferred embodiment of my invention and illustrated the same in the accompanying drawings, certain minor changes or alterations may appear to one skilled in the art to which this invention relates, during the extensive manufacture of the same, and I, therefore, reserve the right to make such changes or alterations as shall fairly fall within the scope of the appended claims.

What I claim is:

1. In a device of the class described, the combination with a handle, of a jaw carrying frame on said handle, a fixed jaw on said frame, a movable jaw comprising a primary and an auxiliary section, each of said sections looped at its inner end around one end of said jaw carrying frame, said primary section provided with an apertured lug, said auxiliary section provided with a slot adapted to receive said lug, a latch on said auxiliary section adapted to enter said lug and hold the sections together, and cloth supporting and twisting means slidably mounted on said handle.

2. In a device of the class described, the combination with a handle, of a jaw carrying frame on said handle, a fixed jaw on said frame, a movable jaw comprising a primary and an auxiliary section, each section having its inner end around an end of said jaw carrying frame, said primary section provided with a longitudinally extending outwardly projecting gripping flange and with a laterally extending apertured lug at its outer end,

said auxiliary section provided with a longitudinally extending outwardly projecting gripping flange and with a slot in its outer end, a latch provided with a tongue pivotally mounted on said auxiliary section, said tongue adapted to enter said lug of the pri-

mary section when the sections are closed together, and mop cloth supporting and twisting means slidably mounted on said handle.

In testimony whereof I hereunto affix my signature.

MILTON BOWEN McCOY.
